[57] CLAIM

The ornamental design for a combined card calendar and container thereof, as shown and described.

DESCRIPTION

FIG. 1 is an exploded perspective view of a combined card calendar and container therefor showing my new design;

FIG. 2 is an enlarged bottom plan view thereof, of the container shown in FIG. 1;

FIG. 3 is an enlarged end elevational view of one of the cards shown in FIG. 1;

FIG. 4 is an enlarged bottom plan view of one of the cards shown in FIG. 1;

FIG. 5 is an enlarged side elevational view of one of the cards shown in FIG. 1;

FIG. 6A is a slightly enlarged top plan view of one half of the cards shown in FIG. 1 in assembled condition; and

FIG. 6B is a slightly enlarged plan view of the second half thereof.
